FASTENING MEANS

Kurt Emde, Itasca, Ill., assignor to Zenith Radio Corporation, a corporation of Illinois

Application December 31, 1943, Serial No. 516,377

6 Claims. (Cl. 24—3)

This invention relates to fastening means and in particular to clasp supporting arrangements.

In such wearable apparatus as hearing aids, wherein such apparatus is carried differently on different users in accordance with their particular taste and particular wearing apparel, it is desirable to have a fastening device or clip which satisfactorily holds the wearable apparatus in all desired positions. Accordingly, an object of the present invention is to provide a universal fastening device for apparatus arranged to be carried on a person.

Another object of the present invention is to provide an improved removable fastening device for such apparatus arranged to be worn by an individual.

The features of the present invention which are believed to be novel are set forth with particularity in the appended claims. This invention itself, both as to its organization and manner of operation, together with further objects and advantages thereof, may best be understood by reference to the following description taken in connection with the accompanying drawing in which:

Figure 1 shows a fastening device or clip embodying this invention on hearing aid apparatus;

Fig. 2 shows the opposite side of the hearing aid apparatus shown in Fig. 1 with means for receiving the fastening device or clip embodying the present invention;

Fig. 3 is a side view of the apparatus shown in Fig. 1 embodying the present invention;

Figs. 4 and 5 are enlarged views partly in section of apparatus embodying the present invention, and are taken substantially on line 4—4 of Figure 1. Figure 4 shows the clip 10 in the same relative position as is shown in Figure 3 in its normal position but Figure 5 shows the clip structure of Figure 4 in its open position to allow insertion of, for example, the wearing apparel of a wearer of a hearing aid;

Fig. 6 is a view in elevation taken in the direction of the arrow in Fig. 4; and

Fig. 7 is a view in elevation of the fastening device or clip embodying this invention.

The fastening device or clip incorporating the present invention has particular applicability in hearing aid apparatus which is of small size for insertion in a pocket of the user. In such case, the fastening device or clip is arranged to engage the user's wearing apparel and to maintain the hearing aid apparatus in some convenient position for the reception of sound waves. In some instances, the user desires to insert the hearing aid apparatus in his pocket and to use the fasten-

ing device or clip to secure the apparatus in his pocket, while in other instances the user either has no convenient pocket within which to place the apparatus or does not desire to place it within an available pocket and in such latter case the apparatus is supported in operating position solely by cooperation of the clip or fastening device with the user's wearing apparel.

The fastening device or clip 10 has two projections 11 and 12 arranged to be inserted into suitably arranged openings 13 and 14 in the wall or closure member 15 of a hearing aid or like apparatus and to be held in operative position by engagement of the projections 11 and 12 with wall or closure member 15. It is noted that the projection 12 is integrally formed with the flat sheet member 16 and extends at an acute angle from such sheet member 16 in a direction opposite to the direction which projection 11 extends. It is noted further that projections 11 and 12 are disposed on the same side of sheet member 16 and further that projection 12 forms a resilient clamp with the sheet member 16 whereby the sheet member 16 may be clamped resiliently and releasably to a supporting wall or the like. It is understood that the wall 15 may be a part of a device other than hearing aid apparatus, that the present invention is not limited to use in hearing aid apparatus but has general utility and that, in a broad sense, wall 15 comprises a support having an inner surface 15A and outer surface 15B.

The clip or fastening device 10 comprises two relatively movable parts. One of such parts comprises a flat thin sheet member 16 having the integrally formed projections 11 and 12 and a pair of oppositely disposed integrally formed apertured ears 17 and 18, and the other one of such parts comprises a spring biased lever 19 having one of its ends 21 suitably knurled at 23 for engagement with wearing apparel, having the other one of its ends 22 suitably knurled at 23A for engagement by the user's finger, and having a pair of oppositely disposed apertured ears 24 and 25 intermediate its ends for the passage of pivot pin 26. Pivot pin 26, having prestressed coil spring 30 with its ends 31 and 32 wound around it, passes through ears 17, 18 and ears 24, 25 (Fig. 6) and has its ends enlarged so that it provides a permanent pivot for relative movement between member 16 and lever member 19.

It is noted that the projection 11 is "L-shaped" and is broadly "hook-shaped." It is noted further that the member 16 forms a clasp supporting member.

Prestressed coil spring 30 wound around pivot 26 has one of its ends 31 engaging lever member 19 and the other one of its ends 32 engaging member 16 so that the end 21 of lever member 19 is normally pressed into engagement with member 16 or presses in a clamping manner the wearer's clothing against the wall 15 upon which the fastening device 10 is mounted.

When mounted on the wall or apertured support or closure member 15, the pivoted lever member or wearing apparel engaging member 19 is normally in the position shown in Fig. 4 wherein end 21 is pressed against any wearing apparel or other supporting means which is inserted between spring biased pivoted lever 19 and the wall or closure member 15.

Spring biased end 21 of lever 19 is displaced from normal engagement with wall 15 by pressing end 22 to the right in Fig. 4, in which case member 19 pivots around pivot pin 26 against the action of prestressed coil spring 30 and ultimately assumes the position shown in Fig. 5 where end 22 engages the supporting member 15.

One of the particular features of the present invention is the ease with which the fastening device or clip 10 may be removed from the hearing aid or other device to which it is attached. For example, in the hearing aid apparatus shown in Figs. 1 and 2, the clip 10 may be removed from the front as shown in Fig. 1, wherein it is effective to secure the hearing aid apparatus within the user's pocket without interfering with sound transmitted to a microphone located behind panel 35 and be fastened to the back of the same hearing aid apparatus provided with the same type of apertures 13, 14 and 27, 28 respectively on the front and back sides of such hearing aid apparatus.

The clip or fastening device, shown in Fig. 7 detached from the structure it is arranged to support, is readily and easily mounted on the wall or closure member 15 by (1) inserting projection 12 into opening 14, (2) pressing the composite clip in the downward direction in Fig. 4 until the projection 11 is in position to be inserted through opening 13, (3) passing projection 11 through opening 13, and (4) then releasing the composite clip 10 in which case the upstanding portion of projection 11 is pressed upward due to the resilient nature of projection 12 to assume the position shown in Fig. 4.

The fastening device or clip 10 is easily detached from wall 15 in Fig. 4 by (1) moving the device 10 downward relative to wall 15, in which case projection 12 is deformed within its resilient limits to a point where projection 11 may be passed through opening 13 and then by (2) pivoting the entire clip 10 at the contact point between projection 12 and wall 15 so as to pass projection 11 through opening 13 and then (3) sliding projection 12 out of opening 14.

It is noted that opening 13 is slightly larger than the upstanding portion of projection 11 in Fig. 4 so as to allow passage of projection 11 therethrough. Opening 14 is defined by a curved upper wall 40 for guiding projection 12 in the process of mounting clip 10 on wall 15 and by a portion 41 of reduced wall thickness for engagement between resilient projection 12 and wall 15. It is noted further that the openings 13, 14 on the one hand and openings 27 and 28 on the other hand are spaced apart a distance slightly less than the distance between the ends of projections 11 and 12.

While particular embodiments of the present invention have been shown and described, it will

be obvious to those skilled in the art that changes and modifications may be made without departing from this invention in its broader aspects, and therefore the aim in the appended claims is to cover all such changes and modifications as fall within the true spirit and scope of this invention.

I claim:

1. In a clasp supporting arrangement a member having integrally formed thereon a pair of oppositely extending projections, one of said projections being resilient and extending from a point intermediate the ends of said member on one side thereof at an acute angle therewith in the direction of one end of said member, the other projection extending from said one side at the other end of said member and being L-shaped, with the vertical portion of the L extending substantially perpendicular to the plane of said thin sheet member and the horizontal portion of the L extending substantially parallel to the plane of said sheet member in a direction opposite to the direction in which said resilient projection extends.
2. In a clasp supporting arrangement a thin sheet member having integrally formed thereon a pair of oppositely extending projections, one of said projections being resilient and extending from a point intermediate the ends of said member on one side thereof at an acute angle therewith in the direction of one end of said member, the other projection extending from said one side at the other end of said member and being hook-shaped.
3. In a clasp supporting arrangement, a thin sheet member having integrally formed thereon a pair of oppositely extending projections, one of said projections being resilient and extending from a point intermediate the ends of said member on one side thereof at an acute angle therewith in the direction of one end of said member, the other projection extending from said one side at the other end of said member and being hook-shaped, said one projection being integrally formed with said sheet member and forming therewith a resilient clamp whereby said sheet member may be clamped resiliently and releasably to a supporting wall or the like.
4. The combination of a clasp supporting member with an apertured support having an inner and an outer wall surface, said clasp supporting member being of thin sheet material and having integrally formed thereon a pair of oppositely extending projections, one of said projections being resilient and extending from a point intermediate the ends of said member on one side thereof at an acute angle therewith in the direction of one end of said member, the other projection extending from said one side at the other end of said member and being L-shaped with the vertical portion of the L extending substantially perpendicular to the plane of said thin sheet member and the horizontal portion of the L extending substantially parallel to the plane of said sheet member in a direction opposite to the direction in which said resilient projection extends, said support having a pair of apertures spaced a distance slightly less than the distance between the ends of said projections, one of said apertures having its opening area and shape slightly greater than the projected area and shape of said horizontal portion of said L and the other one of said apertures having its opening area and shape slightly greater than the projected area of said resilient projection, said acute angle and the wall thickness of said apertured support

being so dimensioned that insertion of said resilient projection through its corresponding opening from the outer wall of said support to engagement with the inner wall of said support results in stressing of said resilient projection, whereby said clasp supporting member may be attached to said apertured support by initially inserting the free end of said resilient projection from the outer side of said support into its corresponding opening into sliding resilient engagement with the inner wall surface of said support thereby stressing said resilient projection until said L-shaped projection comes in registry with its opening, then inserting said L-shaped projection through its corresponding opening and then moving said horizontal portion of the L into sliding engagement with said inner wall surface wherein it is held in spring biased condition due to the stressed condition of said resilient projection.

5. The combination of a clasp supporting member with an apertured support having an outer and an inner wall surface, said clasp supporting member having formed thereon a pair of projections, one of said projections being resilient and extending from one side of said member at an acute angle therewith in the direction of one end of said member to form a resilient clamping member, the other projection extending from said one side near the other end of said member and being hook-shaped, said support having a pair of apertures spaced a distance slightly less than the distance between the ends of said projections, one of said apertures having its opening area and shape slightly greater than the projected area and shape of said hook-shaped projection 35

and the other one of said apertures having its opening area and shape slightly greater than the projected area of said resilient projection, said acute angle and the wall thickness of said apertured support being so dimensioned that insertion of said resilient projection through its corresponding opening from the outer wall of said support to engagement with the inner wall surface of said support results in stressing of said resilient projection, whereby said clasp supporting member may be attached to said apertured support by initially inserting the free end of said resilient projection from the outer side of said support into its corresponding opening into sliding resilient engagement with the inner wall surface of said support thereby stressing said resilient projection until said hook-shaped projection comes into registry with its opening, then inserting said hook-shaped projection through its corresponding aperture and then moving said hook-shaped projection into sliding engagement with said inner wall surface wherein it is held in spring biased condition due to the stressed condition of said resilient projection.

10 15 20 25 30 35 6. In a clasp supporting arrangement, a thin sheet member having integrally formed thereon a pair of oppositely extending projections, one of said projections being resilient and extending from a point intermediate the ends of said member on one side thereof at an acute angle therewith in the direction of one end of said member, the other projection extending from said one side in the proximity of the other end of said member and being hook-shaped.

KURT EMDE.
